UNITED STATES PATENT OFFICE.

ORGERIO ABBADINI, OF FAIRBANK, PENNSYLVANIA.

WIRE CONNECTION FOR ELECTRIC PLUGS.

Application filed November 11, 1922. Serial No. 600,330.

To all whom it may concern:

Be it known that I, ORGERIO ABBADINI, a citizen of the United States, residing at Fairbank, in the county of Fayette and 6 State of Pennsylvania, have invented certain new and useful Improvements in Wire Connections for Electric Plugs; and I do hereby declare the following to be a full, clear, and exact description of the invention, such as will enable others skilled 10 in the art to which it appertains to make and use the same.

This invention has relation to a connector for electric wires, which will admit of 15 the wire being quickly connected and readily disconnected as may be required, and which will avoid torsional strain as provision is had for a relative turning of the parts while at the same time maintaining firm electric connection.

Specifically considered, the invention relates to means whereby an electric wire may be connected to a plug which cooperates with a socket, said plug being required 25 to be rotated when coupling or uncoupling the same when connecting or disconnecting the wire.

The invention provides a connection which operates by a snap action and which 30 is free to turn, whereby to prevent any torsional strain on the wire or joint.

Other objects and advantages will be apparent and suggest themselves as the nature of the invention is understood.

35 While the drawings illustrate an embodiment of the invention it is to be understood that in adapting the same to meet different conditions and requirements, various changes in the form, proportion and 40 minor details of construction may be resorted to without departing from the nature of the invention.

Referring to the accompanying drawings forming a part of the application,

45 Figure 1 is a detail view of an electric wire connection embodying the invention, the parts being separated,

Figure 2 is an enlarged sectional detail, the parts being connected,

50 Figure 3 is an end view of a coupling member,

Figure 4 is a detail plan view of the socket spring, and

Figure 5 is a sectional detail of a modification wherein the connection is applied to a double contact plug.

Corresponding and like parts are referred to in the following description and designated in the several views of the drawings by like reference characters.

60 The numeral 1 designates the usual plug of an electric wire connector, the same being provided at opposite sides with studs 2 for cooperation with the bayonet slots of a cooperating socket in a manner well understood. This plug may be of any insulating material and is provided with a contact 3 which may be single, as illustrated in Figures 1 and 2, or double, as indicated in Figure 4, accordingly as the plug is of 65 the single or double contact type. A cap 4 is threaded to an end of the plug 1 and is apertured for the passage of the wire 5 to be connected to the plug 1.

70 In accordance with the present invention, a stud 6 is integral with, riveted to or otherwise applied to the plug 1 and is in electric connection with the contact 3. A socket 7 is soldered or otherwise applied to the terminal of the wire 5 and is adapted to 75 engage the stud 6 by a snap action. The stud 6 and co-acting socket 7 may be of 80 any type or make common in the art of snap or separable fastenings. For instance socket 7 has an entrance opening 7^a for the ball of stud 6 and the socket contains a wire spring 8^a having jaws 9^a between which the ball of the stud 6 is adapted to 85 be forced upon engagement and disengagement with the socket, the jaws 9^a tending 90 to assume the position shown in Figure 4 so that they will contract about the stud inwardly of the head, to retain the stud as shown in Figures 2 and 5. The parts 6 and 95 7 may be attached to the cooperating parts 1 and 5 in any preferred way and admit of the wire 5 being connected to the plug 1 by a snap action, or instantly disconnected therefrom, the connection admitting of the plug 1 turning to effect coupling or uncoupling 100 thereof without creating any torsion on the wire 5. As shown most clearly in Figure 2, the cap 4, besides protecting the joint, functions to secure and prevent casual separation thereof, since the socket 7 is adapted 105 to be clamped between the cap and the adjacent end of the plug 1. As hereinbefore stated, Figures 1 and 2 show the invention applied to a single contact plug, whereas Figure 4 shows it applied to a double contact plug, the connecting means being 110 substantially the same in each instance.

What is claimed is:

1. In combination, an electric plug provided with a contact, a stud applied to the plug and in electric connection with the contact thereof, an electric wire, a socket applied to the electric wire and adapted to be coupled to said stud by a snap action and to relatively turn to prevent torsional strain on the wire, and a cap receiving the wire and having screw thread connection with the plug and adapted to prevent casual separation of the socket from the stud.
2. In combination, an electric plug provided with a contact, a second contact applied to said plug and in electric connection with the first contact, an electric wire, a contact applied to the electric wire and adapted to connect to the second contact for turning movement relative thereto to prevent torsional strain on the wire, a cap through which the wire passes, and said cap having supported connection with the plug and extended inwardly to overlap the lower surface of the second contact to prevent casual separation of the second contacts, said cap being turnable independently of the contacts and wires.

In testimony whereof I affix my signature.

ORGERIO ABBADINI.
